US00D945483S

(12) **United States Design Patent** (10) **Patent No.:** **US D945,483 S**
(45) **Date of Patent:** **** Mar. 8, 2022**

(54) **DISPLAY SCREEN OR PORTION THEREOF
WITH ICON**

(71) Applicant: **Apple Inc.**, Cupertino, CA (US)

(72) Inventors: **Freddy Anzures**, San Francisco, CA (US); **Greg Apodaca**, Mountain View, CA (US); **Ismael Basso**, San Francisco, CA (US); **Imran Chaudhri**, San Francisco, CA (US); **Jonathan P. Ive**, San Francisco, CA (US); **Matthew Dean Rohrbach**, San Francisco, CA (US); **Christopher Daryl Soli**, Mountain View, CA (US); **Wan Si Wan**, Sunnyvale, CA (US); **Christopher Wilson**, San Francisco, CA (US)

(73) Assignee: **Apple Inc.**, Cupertino, CA (US)

(**) Term: **15 Years**

(21) Appl. No.: **29/706,725**

(22) Filed: **Sep. 23, 2019**

CPC G06F 3/48; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/0486; G06F 3/0487; G06F 3/0488; G06F 3/04883; G06F 3/04886

CLAIM

The ornamental design for a display screen or portion thereof with icon, shown and described.

DESCRIPTION

The FIGURE is a front view of a display screen or portion thereof with icon showing the claimed design.

The broken lines in the FIGURE show a display screen or portion thereof, and form no part of the claimed design.

1 Claim, 1 Drawing Sheet
